UNITED STATES PATENT OFFICE.

MORRIS S. TROP, OF BROOKLYN, NEW YORK, ASSIGNOR TO TROP CHOCOLATE CO., OF BROOKLYN, NEW YORK.

DESIGN FOR A WRAPPER.

53,024.

Specification for Design.

Patented Feb. 25, 1919.

Application filed October 4, 1918. Serial No. 256,908. Term of patent 14 years.

To all whom it may concern:

Be it known that I, MORRIS S. TROP, a citizen of the United States, and a resident of the city of New York, borough of Brooklyn, in the county of Kings and State of New York, have invented a new, original, and ornamental Design for a Wrapper, of which the following is a specification.

The design relates to wrappers such as the paper wrappers of bars of plain and other chocolates and like confections.

Reference is to be had to the accompanying drawing forming part of the specification in which the figure is a perspective view of my new design.

I claim:

The ornamental design for a wrapper substantially as shown.

MORRIS S. TROP.
